METHOD FOR DRIVING ROCK TUNNELS

Robert D. Budd, Denver, Colo., assignor to Goodman Manufacturing Company, Chicago, Ill., a corporation of Illinois

Application August 15, 1951, Serial No. 241,976

7 Claims. (Cl. 61—42)

1

This invention relates to improvements in systems and apparatus for driving large diameter rock tunnels.

Until the past few years, the maximum size of rock tunnels has usually been approximately that required for railroad or vehicular use, but with the recent increase in large irrigation projects, tunnels of forty or more feet have been driven, or are in contemplation.

It is common practice to drive rock tunnels by blasting either along a single vertical heading or face, or in which the heading consists of a series of benches having vertical and horizontal surfaces. When the size of a tunnel reaches beyond ordinary proportions, it becomes extremely dangerous to drive the tunnel by conventional methods, because overhanging brows, or poor rock structure at the heading, may endanger the workmen. Also, where the bench method is employed, considerable labor is required to remove the loose material which becomes lodged on the several benches after blasting operations.

A further difficulty in driving large diameter tunnels is that the movable work scaffold, commonly termed "a drill jumbo," for supporting drills and workmen at several working levels, becomes extremely heavy and unwieldy, and the difficulty of removing the loose material from the heading increases with the height and size of the drill jumbo.

Another difficulty with conventional methods is that of setting up arched roof supports usually employed as the working face is advanced.

In carrying out my invention for use in extremely large diameter tunnels I employ a forwardly and upwardly sloped heading for the dual purpose of eliminating dangerous overhanging brows and of providing working space for the installation of roof steel at the same time that mucking is being carried out underneath. Additionally, I employ separate upper and lower jumbos, each working against approximately half the heading, the upper jumbo being supported on wing benches or berms running along the sides of the tunnel at the half-way level, the lower jumbo running on track in the floor.

Among the advantages of drilling a tunnel in accordance with this invention are the following:

1. Where access to the tunnel is through a shaft, operations can be carried out from a single, final grade, making only one shaft station, at the level of the lower jumbo, necessary.

2. Tunnel facilities such as air, water and power lines and track need be installed only once, namely at the lower level.

3. Drainage will be established on the final invert grade at once so that there will be no flow over benches as is the case under wet conditions under conventional tunneling practice.

4. Roof support steel can be preliminarily in-

2

stalled on the upper jumbo at a distance back from the heading and then moved up into place and lifted and set with a minimum of time and labor, even while mucking is being carried out at the lower level.

5. Drilling of the entire top half of the tunnel can be carried out while mucking is being done underneath.

6. By using two jumbos working on two levels, each jumbo will be lighter and consequently more maneuverable than in conventional practice where a single large jumbo is used.

7. The top jumbo can be moved to the face immediately after blasting and mucking can proceed underneath it while the bottom jumbo may be kept at a distance back from the face and used as a cherry picker for lifting empty cars over the locomotive.

My improved system and apparatus will now appear as the following description proceeds:

The invention may best be understood by reference to the accompanying drawings, in which:

Figure 1 is a vertical transverse section of a rock tunnel in the course of driving operations, and illustrative of a typical arrangement of the driving apparatus to be employed therein;

Figure 2 is a longitudinal section of the tunnel shown in Figure 1, but drawn to a smaller scale, partly in section.

30 Referring now to details of the embodiment of my invention illustrated in the drawing, the tunnel may be advanced with any conventional cross-sectional shape such as a generally circular form B, the final dimensions of the material to be excavated being indicated by the solid roof line 1, and a continued arcuate floor and side wall line indicated in full lines at 2 in dotted lines at 3.

With exceptions to be presently described, the tunnel is driven by drilling the heading or face simultaneously at a plurality of spaced points followed by blasting and then "mucking" or removing the resulting loose material from the face, and then repeating the drilling, blasting and mucking operations.

45 In my improved system however, the working face or heading, indicated generally at 5 in Figure 2, is battered back or inclined forwardly and upwardly on about a one-half to one slope or at an angle of approximately 60 degrees to the horizontal, so that no overhanging brows can occur,

so that the hazard of falling rock from the face will be minimized, and so that no horizontal surfaces or benches will be left on the face or require special mucking operations to remove the loose material from such benches following each blast.

50 A further novel feature of my tunneling system consists of leaving two side benches 10, 10 along the opposite side walls of the tunnel as the face is advanced. The primary purpose of these benches is to support a top arch drill jumbo indi-

60

cated generally at 11. A track 12 is laid on each side bench 10 for supporting a plurality of aligned wheels 14, 14 at opposite sides of the top arch jumbo to permit the latter to be rolled to and fro relative to the face.

The proportions of these benches 10, 10 may vary somewhat with the size of the tunnel, as for instance each bench may be from 4 to 6 feet in width. Said benches are preferably disposed substantially at the widest part of the tunnel, commonly termed the "spring line," approximately midway between the roof and floor. Certain benches are carried on relatively steep, inwardly sloping walls 15, 15 which are preferably made as steep as practical for supporting the benches and yet insuring substantial width at the bottom level of the tunnel where other trackways are laid, as will presently be described.

The top arch jumbo 11 may consist of any suitable framework adapted to support a plurality of drills of conventional construction at properly spaced points for the usual drilling operations at the heading. The top arch jumbo has its forward portion disposed at an angle roughly corresponding to that of the sloping heading or face 5 and is preferably provided with a plurality of superposed platforms 16, 16 for convenience of the men working at different levels on the heading. In the form shown herein, three such platforms are indicated which extend progressively nearer the heading toward the top of the jumbo. The number of such platforms may, of course, be varied with the size of the tunnel.

From this top arch jumbo 11, steel arch roof supports 20 of conventional form, including segments 20a bolted or welded together at junctures 20b, may be erected as required, excepting that with my improved system the lower legs 21 of said arched roof supports can be supported directly on the side benches 10, 10 or on blocks 10a resting on said benches. Steel or wood lagging (not shown) will be applied between the supports 20 and the rock.

A second or lower drill jumbo, indicated generally at 25, is made of proper dimensions to fit within the space between the side benches 10. This lower jumbo is preferably the gantry type having an open central arched portion 26 permitting longitudinal passage of one or more mucking machines or cars to and fro relative to the heading independently of the movement of the lower jumbo. In the form shown herein, the lower jumbo 25 is wide enough to span two pairs of tracks 28, 28 and 29, 29, laid side by side along the tunnel floor. The upright side legs 30, 30 of the lower jumbo are provided with a plurality of wheels 32, 32 mounted for movement along other tracks 33, 33 on the bottom of the tunnel. The two pairs of tracks 28, 28 and 29, 29 disposed between the open arch portion 26 of the lower jumbo provide space for two trackways, indicated in dotted outlines at 34 and 35, respectively, in Figure 1, along which trackway mucking operations may be conducted by mucking machines or cars independently of the movement of the lower jumbo 25. Manifestly, piles of spoil will accumulate on the benches 10 after each blasting operation. These piles of spoil can be cleared from the benches by means of plows 38, 38, indicated in Figures 1 and 2, which plows are mounted on the forward end of the upper drill jumbo 11 and depend therefrom in horizontal alignment with the benches 10, so that the muck remaining on the benches after the blast will be scraped toward the center of the tunnel and fall along the inclined

side walls 15, 15 into the space below the top jumbo 11.

Both the top and bottom jumbos 11 and 25 can be moved in any suitable manner as by means of a hoist, not shown.

It will be understood from the above description that the construction of the drill jumbos, and the machinery and apparatus utilized therewith, have only been roughly outlined to indicate their general structure and use in connection with my improved system, but that details of such drill jumbos and apparatus may vary in any manner to suit particular problems which may be met.

Among the advantages of my improved tunneling system are the following:

The inclined faces on the heading 5 and on the side benches 10 will minimize the hazard of rock becoming dislodged and rolling on the men in the working space below. The inclined heading, as shown, provides no place for storage of loose material or muck. All such muck will slide on this face directly to the bottom where it can be picked up by the mucking machine working below the top jumbo. The inclined heading, therefore, provides a safe working condition for the drilling crew which must follow the mucking. Highway cuts are commonly scaled and considered safe when cut on one-quarter to one slope and little hazard is encountered when working to the side or below them.

The side benches 10 provide a solid stable mounting for the top jumbo, as well as additional support for the face of the tunnel until such time as a necessary roof arch can be set. Since such roof arch is commonly set only in the top half of the tunnel, these benches permit the roof arch to be set very close to the brow of the face. Without the benches, it would be difficult to place the roof arch so as to permit one jumbo, herein in the upper jumbo, to reach the entire inclined working face.

A further and important advantage of my system is that the tunnel can be cut down to the bottom grade immediately and edged along a single working face extending the entire height of the tunnel, instead of advancing the heading in two steps, as has often been considered necessary with large tunnels. Accordingly, my system makes it unnecessary to lay tracks on the top heading, then remove the tracks and install haulage on the bottom grade. Also portal cuts can be taken out to the bottom grade before the tunnel work is started. Shaft stations can be located on the bottom grade, thus obviating the usual necessity of lowering the shaft station in a two-stage operation. This makes it possible to install air lines or ventilation lines, drainage ditches, pump lines, etc., only once during the driving of the tunnel, and sumps can be cut down to the final elevation for the driving operation.

The side benches 10, 10 can be removed to the completed side wall dimensions, as indicated in Figure 1, by either of two methods; one, the tunnel can be driven to its entire length and the benches can be taken up on retreat along the final clean-up; or two, these side benches may be removed behind the heading at the same time that the tunnel is progressing, so long as sufficient bench is left close to the heading to move the upper jumbo into the clear for blasting; in this method, mucking of the side benches would be carried out when the mucking machines are

5

moved back from the face during the drilling period in the main heading.

As described above, one of the important advantages of this invention is the fact that roof supporting steel can be installed at the same time that muck is being removed from the lower level. This is carried out as follows: when the upper jumbo is away from the face during a blasting operation, the arched roof supports may be bolted loosely together atop a wheeled carriage 50 mounted to run forward and backward along the top level of the upper jumbo. By bolting the joints 20b loosely the arches will droop so as to fit in the space between the previously installed arches and the upper jumbo, all as shown in dotted lines in Figure 1. When it is moved in place, jacks 51, 51 carried by the vehicle 50 may be operated to lift the roof arch against the roof following which the junctures 20b may be tightened and set upon blocks 10a at the proper height.

In removing muck separate sets of locomotive drawn cars will operate behind each mucking machine on the tracks 28, 28 and 29, 29. During the mucking operation the lower jumbo may be moved a distance from the face to function as a "cherry picker" in the usual manner involving lifting an empty car to the position indicated 53 in Figure 2 while the locomotive and the rest of the cars run underneath.

Although I have shown and described certain embodiments of my invention, it will be understood that I do not wish to be limited to the exact construction shown and described, but that various changes and modifications may be made without departing from the spirit and scope of the invention as defined in the appended claims.

I claim:

1. The method of driving rock tunnels, which consists in advancing the heading with its working face disposed at an upwardly and forwardly inclined angle, leaving side benches intermediate the roof and floor of the tunnel, supporting separate upper and lower wheeled drill jumbos for independent to-and-fro movement along said benches and said floor, respectively, while attacking said face from the front ends of said jumbos to deposit loose material detached from the heading upon the floor of the tunnel, and removing said loose material from the heading along the floor of the tunnel.

2. The method of driving rock tunnels, which consists in advancing the heading with its working face disposed at an upwardly and forwardly inclined angle, leaving side benches intermediate the roof and floor of the tunnel, supporting separate upper and lower wheeled drill jumbos for independent to-and-fro movement along said benches and said floor, respectively, while attacking said face from the front ends of said jumbos to deposit loose material detached from the heading upon the floor of the tunnel, removing said loose material from the heading along the floor of the tunnel, and removing said side benches in back of the jumbos to the final width of the tunnel.

3. The method of driving rock tunnels, which consists in advancing the heading with its working face disposed at an upwardly and forwardly inclined angle, leaving side benches intermediate the roof and floor of the tunnel with the inner supporting walls of said benches steeply inclined to the floor of the tunnel, supporting separate upper and lower wheeled drill jumbos for independent to-and-fro movement along said benches and

6

said floor, respectively, while attacking said face from the front ends of said jumbos to deposit loose material detached from the heading upon the floor of the tunnel, also clearing loose material from said side benches by gravity along the inclined inner walls of said side benches with plows carried in front of the upper jumbo, and removing all of said loose material from the heading along the floor of the tunnel.

10 4. The method of driving rock tunnels, which consists in advancing the heading with its working face disposed at an upwardly and forwardly inclined angle, leaving side benches intermediate the roof and floor of the tunnel, supporting separate upper and lower wheeled drill jumbos for independent to-and-fro movement along said benches and said floor, respectively, with said lower drill jumbo spanning a material-removal trackway disposed centrally of the tunnel floor, while attacking said face from the front ends of said jumbos to deposit loose material detached from the heading upon the floor of the tunnel, and removing said loose material from the heading along the material-removal trackway.

25 5. The method of driving rock tunnels, which consists in advancing the heading with its working face disposed at an upwardly and forwardly inclined angle, leaving side benches intermediate the roof and floor of the tunnel, supporting separate upper and lower wheeled drill jumbos for independent to-and-fro movement along said benches and said floor, respectively, erecting a roof arch from the upper jumbo, with the lower ends of said roof arch supported on said side benches, while attacking said face from the front ends of said jumbos to deposit loose material detached from the heading upon the floor of the tunnel, and removing said loose material from the heading along the floor of the tunnel.

40 6. The method of driving rock tunnels, which consists in advancing the heading with its working face disposed at an upwardly and forwardly inclined angle; leaving side benches intermediate the roof and floor of the tunnel; supporting separate upper and lower wheeled jumbos for independent to-and-fro movement along said benches and said floor, respectively; moving said jumbos back from the face and blasting the face to deposit muck on the floor of the tunnel; assembling roof-supporting steel on said upper jumbo, moving the latter back to said face and installing the steel at the roof; and drilling the upper portion of the face with the upper jumbo while mucking at the lower level and employing the lower jumbo as a cherry picker during the mucking operation.

45 7. The method of driving rock tunnels, which consists in advancing the heading with its working face disposed at an upwardly and forwardly inclined angle; leaving side benches intermediate the roof and floor of the tunnel; supporting separate upper and lower wheeled jumbos for independent to-and-fro movement along said benches and said floor, respectively; moving said jumbos back from the face and blasting the face to deposit muck on the floor of the tunnel; moving the upper jumbo back to the face and drilling the upper portion of the face from the upper jumbo while mucking at the floor level and transferring into cars; and employing the lower jumbo as a transfer point to transfer loaded cars from one end of a string of cars to the other during the mucking operation.
